FIG. 4

UNITED STATES PATENT OFFICE.

VICTOR J. KING, OF CEDARVIEW, UTAH, ASSIGNOR OF ONE-HALF TO DAVID P. WHITMORE, OF ROOSEVELT, UTAH.

AIR COMPRESSOR AND VACUUM WATER PUMP.

Application filed May 28, 1925. Serial No. 33,525.

This invention relates to a pump and while capable of general use, it is primarily adapted for lifting or elevating water for irrigating, culinary or other purposes where at the present time and by present methods it is difficult and costly to elevate the water.

Another object is to provide a construction wherein the pump is operable by water, particularly by the dropping of slightly more than half the amount of water used to specifically raise the remaining water as far as the height of the drop.

Still further it is aimed to provide a construction wherein a portion of the water raised may be raised higher through the action of the remainder of the raised water.

A further object is to provide a construction whereby as in the case of a town where impure water is plentiful and good water is at a lower level although inaccessible unless pumped, the impure water may be used to operate or pump the pure water.

Still further it is aimed to provide a construction wherein the principles may be embodied in an air compressor, vacuum pump or otherwise.

Additional objects and advantages will become apparent from a consideration of the description following taken in connection with accompanying drawings illustrating an operative embodiment.

In said drawings:—

Figure 1 is a view of the apparatus in perspective;

Figure 2 is a vertical sectional view;

Figure 3 is a vertical sectional view through a slightly modified form, and

Figure 4 is a vertical sectional view through a further modified form particularly forming an air compressor.

Referring specifically to the drawings, 1 designates an inlet pipe through which water is adapted to flow. Water from said pipe 1 passes through a pipe 2 and a pipe 3, arranged in vertical alinement, the parts being so proportioned that the water from pipe 1 will flow into pipe 2 in a quantity slightly in excess of half thereof while a quantity slightly less than half thereof will pass through the pipe 3 by suction, through the method hereinafter described. Pipe or conduit 2 is in communication with a con-

duit or cylinder 4, substantially midway of the ends of the latter and said conduit 4 at branches 5 and 6 is in communication, respectively, at the bottom of a lower compression tank 7 and a lower vacuum tank 8. The ends of the cylinder or conduit 4 are in communication with forked branches 9 and 10 of an outlet pipe 11.

Alined with the cylinder 4 is a shorter cylinder 12 which, through the medium of a pipe or conduit 13 is in communication with the bottom of the vacuum tank 8. A suitable piston coats with the cylinders 4 and 12, having a shaft or rod 14 slidably disposed in the adjacent end walls, through suitable stuffing boxes 15, of the said cylinders 4 and 12. In spaced relation within the cylinder 4 and rigid on the rod 14 are piston heads 16 and 17 slidable with said rod 14. Said heads 16 and 17 are so arranged that the pipe 2 and pipe 5 may be arranged in communication, or the pipe 2 and the pipe 6 may be arranged in communication. Rod 14 also carries a piston head 18, which is movable therewith and slidably disposed in the cylinder 12. A pipe or conduit 19 of relatively small gage communicates with the tank 7 at the bottom thereof and with the cylinder 12 at the opposite side to the conduit or pipe 13.

Pivoted in the tank 8 as on a rod or shaft 20 is a float lever or arm 21, its float being specifically shown at 22 and arranged to coat with the water therein. Slidably mounted through a suitable stuffing box on tank 8 as at 23, is a link 24 having a curved portion loosely surrounded by an eyelet 25 in the lever 21 and adapted for movement against spaced abutments 26 and 27 on said link. Said link exteriorly of the tank 8 is pivoted at 28 to a detent in the form of a lever 29 pivoted at 30 to a suitable part of the device. This detent at times is adapted for location, as shown in Figure 2, in the rear of an abutment 31 rigid on rod 14 and like the detent 29 is located exteriorly of the apparatus, below the tank 8 and between the cylinders 4 and 12.

In line with the tank 7 is an upper compressed air tank or reservoir 32, while an upper vacuum tank 33 is disposed above the

tank 8. A compressed air conduit 34 rises from the tank 7 and communicates with the tank 32 at the top thereof and a pipe or conduit 35 leads from the top of tank 8 to the top of the tank 33. Conduit 3 communicates with a conduit 36 midway of the ends of the latter and communicating with both the tanks 32 and 33 and at their points of connection are adapted to be closed at times and opened at times through the operation of flap valves 37 and 38, both of the latter being upwardly movable and for instance pivoted to the respective tanks 32 and 33. An upwardly extending outlet 39 is disposed between the tanks 32 and 33 and leads to a suitable elevation designed to conduct water to the point of use or storage. Pipe 39 has branches 40 and 41 respectively in communication with the tanks 32 and 33 at their bottoms. In each branch 40 and 41, a flap valve is provided as at 42 and 43, respectively, said valves preferably being pivoted, and adapted to open in the direction of the arrows, that is to permit the passage at the proper time, of water from the tanks 32 and 33, respectively, upwardly through the pipe 39.

In the operation of the device, say the tanks 7, 8, 32 and 33 contain water to the level indicated and the associated pipes as shown contain water, the water from pipe 1 flows or runs down the pipe 2 into cylinder 4, limited by the position of the piston heads 16 and 17, and then upwardly through branch 5 into the tank 7. Under this condition, the weight of the water in pipes 1 and 2 compresses the air in the tank 7 and forces such compressed air through pipe 34 into tank 32 above the water therein. Such compressed air forces the water from tank 32 through the branch 40, forcing the flap valve 42 open and thence into the pipe 39 to a higher level and point of use. While the said action described is transpiring, water from tank 8 runs through branch 6 to the cylinder 4 at the right of piston head 17 and thence into the branch 10 and outlet conduit 11, which creates a vacuum within the tank 8 above the water therein and which vacuum extends to the tank 33 through the pipe 35, causing a suction on the water in tank 33 which opens check valve 38 and draws water from the pipe 1 up the conduit 3 and conduit 36 into the tank 33 until the tank 8 empties. Emptying of the tank 8 permits the float 22 to lower and the eyelet 25 to elevate so that it contacts with the abutment 26, elevating the link 24 and detent 29 out of engagement with the abutment 31 whereupon vacuum in tank 8 drawing on the water therein through the pipe 13 and cylinder 12, and also assisted by the pressure in tank 7 passing therefrom through pipe 19, slides the rod 14 and piston heads 16, 17 and 18 to the right, thus placing the pipes 1, 2, 4

and 6 and the tank 8 in communication, instead of the pipes 1, 2, 4, and 5 and tank 7 being in communication, whereby the operation of the water, compressed air and vacuum is reversed. These movements being continuous, will keep the water passing continuously through the pipes 11 and 39. 70

In Figure 3 a modification is shown wherein the water may be elevated much higher than in the preceding form. In this modified form, the equivalents of the pipes 34 and 35 are designated 34^a and 35^a, respectively. All of the other parts of the preceding form are used and the same reference characters have been applied thereto. 75 Said pipes 34^a and 35^a have ports 44 and 45, respectively, in communication with the tanks 32 and 33. However, said pipes 34^a and 35^a are extended upwardly and also communicate with tanks 32^a and 33^a which 80 operate in a manner similar to the tanks 32 and 33 and similar parts so as to elevate the water to a greater height. To this end, the pipe 39 is supplanted by a pipe 39^a. Pipe 39 in this instance communicates with a pipe 85 36^a which in turn at its ends communicates with the tanks 32^a and 33^a, at the outlets having upwardly movable flap valves 37^a and 38^a, respectively. Pipe 39^a is in communication with tanks 32^a and 33^a by means 90 of branches 40^a and 41^a, respectively, having flap valves disposed therein operable similar to the valves 42 and 43, at 42^a and 43^a.

In Figure 4, the main principle of my invention is shown as embodied in an air 100 compressor. The parts referred to by numerals 1 to 31, of the previous figures, are all employed with the exception of pipe 3 which is omitted. In lieu of the pipes 34 and 35, pipes or conduits 34^b and 35^b lead 105 from the respective tanks 7 and 8. A horizontally disposed conduit 50 is in communication with the pipes 34^b and 35^b and has an outlet pipe 51^a for compressed air leading to any suitable point of use or storage. 110 In the outer ends of pipe 50, inwardly movable flap valves 51 and 52 are provided while flap valves 53 and 54 are also provided in said pipe 50 between the pipes 34^b and 35^b and also being inwardly opening. Said 115 flap valves may be of any suitable type but are preferably pivoted at their tops.

During the operation of the device described as an air compressor, the air compressed by the tanks 7 and 8, with the conduits 1, 2 and 5 in communication, will pass upwardly through the pipe 34^b past valve 53, through pipe 50 and then through pipe 51^a with valves 51 and 54 remaining closed. On the contrary when the pipes 1, 2, 4 and 6 120 are in communication with the tank 8, the compressed air flows from tank 8 through pipe 35^b, into pipe 50, past valve 54 and into pipe 51^a. During the latter operation, air is 125 admitted by the automatic opening of valve 130

51 while in the former operation air is automatically admitted by opening of the valve 52.

Various changes may be resorted to provided they fall within the spirit and scope of the invention.

What is claimed is:—

1. An apparatus of the class described comprising tanks, means for the flow of 10 water to and from said tanks, alternately and automatically operable means to control the flow of said water to the respective tanks, and means controlled by the height of water in one of said tanks for placing 15 the tanks in communication for alternate compression of air and creation of a vacuum therein.

2. An apparatus of the class described comprising tanks, means for the flow of 20 water to and from said tanks, automatically operable valve means alternately placing the tanks in communication with the first mentioned means, and means controlled by the height of water in one of said tanks for 25 placing the tanks in communication for alternate compression of air and creation of a vacuum therein.

3. An apparatus of the class described comprising tanks, means for the flow of water 30 to and from said tanks, automatically operable valve means in the first mentioned means to alternately place the first mentioned means in communication with the tanks, and means controlled by the height 35 of water in one of said tanks for placing the tanks in communication for alternate compression of air and creation of a vacuum therein.

4. An apparatus of the class described 40 comprising tanks, means for the flow of water to and from said tanks, automatically operable valve means in the first mentioned means to alternately place the first mentioned means in communication with the 45 tanks, means placing the tanks in communication for alternate compression of air and creation of a vacuum therein, a pipe in communication with said tanks and including a cylinder, and a piston operable in said 50 cylinder and with said valve means, said piston being subject to the vacuum created within the tank.

5. An apparatus of the class described 55 comprising tanks, means for the flow of water to and from said tanks, automatically operable valve means in the first mentioned means to alternately place the first mentioned means in communication with the tanks, means placing the tanks in communication 60 for alternate compression of air and creation of a vacuum therein, a pipe in communication with said tanks and including a cylinder, a piston operable in said cylinder and with said valve means, said piston 65 being subject to the vacuum created within

the tank, and means to normally prevent actuation of the valve means subject to the action of the water within the tanks.

6. An apparatus of the class described comprising tanks, means for the flow of 70 water to and from said tanks, a valve in said means to alternately place said means in communication with the tanks, a float in one of the tanks, means controlled by said float to prevent movement of the valve when 75 the water level in said tank is a predetermined height, the lowering of the water level serving to displace said float means, and means operable thereafter by a created vacuum in said valve means to thereby alter- 80 nate the flow of water

7. An apparatus of the class described comprising tanks, a conduit in communication with both tanks, means to supply 85 water to said conduit, a piston valve device 85 slidable in said conduit to cause the water to flow alternately into said tanks, an outlet pipe in communication with the ends of said conduit, a detent coacting with said valve, a float actuated means in one of the 90 tanks to control the actuation of said detent, and means to shift said valve device subject to the vacuum within said tanks, and means 95 placing the tanks in communication for alternate compression of air and creation of a vacuum therein.

8. An apparatus of the class described comprising motive creating tanks and water elevating tanks, pipe means connecting said tanks in pairs, a cylinder connecting the motive creating tanks, means to deliver water to said cylinder, means to discharge water from said cylinder, means in said cylinder to control the flow of water therefrom to one of said motive creating tanks and to 105 simultaneously discharge water from the other tank, and means controlled by the height of the water in one of said tanks to actuate the last mentioned means and thereby alternate the flow of water to and from 110 said tanks.

9. An air compressor having a plurality of tanks, means for the flow of water thereto, a control valve associated with said means operable automatically to direct the water 115 to the tanks alternately, an outlet means in communication with said tanks, a conduit having an air intake valve for each tank and arranged in communication with each tank, flap valves controlling the outlet from each 120 tank, an outlet pipe leading from said conduit, the water serving to alternately compress air and create a vacuum in said tanks, a pipe in communication with both tanks 125 having a cylinder, a piston valve controlling said valve means operable in said cylinder and subject to the vacuum and compression in the apparatus.

In testimony whereof I affix my signature.
VICTOR J. KING,
